(57) **CLAIM**

The ornamental design for a heart novelty, as shown and described.

DESCRIPTION

FIG. 1 shows a perspective view of the heart novelty in accordance with the new design.

FIG. 2 shows a front view of the heart novelty of FIG. 1. FIG. 3 shows a top view of the heart novelty of FIG. 1. FIG. 4 shows a bottom view of the heart novelty of FIG. 1. FIG. 5 shows a side view of the heart novelty of FIG. 1. FIG. 6 shows a perspective view of the outer heart portion of the heart novelty of FIG. 1, shown separately for completeness of illustration;

FIG. 7 shows a front view of the outer heart portion of the heart novelty of FIG. 6.

FIG. 8 shows a top view of the outer heart portion of the heart novelty of FIG. 6.

FIG. 9 shows a bottom view of the outer heart portion of the heart novelty of FIG. 6.

FIG. 10 shows a side view of the outer heart portion of the heart novelty of FIG. 6.

FIG. 11 shows a perspective view of the inner heart portion of the heart novelty of FIG. 1, shown separately for completeness of illustration;

FIG. 12 shows a front view of the inner heart portion of the heart novelty of FIG. 11.

FIG. 13 shows a top view of the inner heart portion of the heart novelty of FIG. 11.

FIG. 14 shows a bottom view of the inner heart portion of the heart novelty of FIG. 11.

FIG. 15 shows a perspective view of the base portion of the heart novelty of FIG. 1, shown separately for completeness of illustration;

FIG. 16 shows a perspective view of the base portion of the heart novelty of FIG. 1.

FIG. 17 shows a front view of the base portion of the heart novelty of FIG. 16.

FIG. 18 shows a top view of the base portion of the heart novelty of FIG. 16; and,

FIG. 19 shows a side view of the base portion of the heart novelty of FIG. 16.

The dashed lines shown in the drawings illustrate environmental structure and form no part of the claimed design.

1 Claim, 5 Drawing Sheets
